UNITED STATES PATENT OFFICE.

JOHN T. HENDERSON, OF CATSKILL, NEW YORK.

DESIGN FOR A SPOON, &c.

SPECIFICATION forming part of Design No. 21,226, dated December 8, 1891.

Application filed April 21, 1891. Serial No. 389,843. Term of patent 7 years.

To all whom it may concern:

Be it known that I, JOHN T. HENDERSON, a citizen of the United States, residing at Catskill, in the county of Greene and State of New York, have invented and produced a new and original Design for Handles of Spoons, &c., of which the following is a specification, reference being had to the accompanying drawings, forming part thereof.

10 Figure 1 is a view of the obverse side of the handle and showing my design for the same. Fig. 2 is a view of the reverse side of the handle and showing my design for the same, these views being deemed necessary to 15 illustrate my design for the handle.

In this design for the two sides of the handle A the leading features in the design for the obverse side is the figure e of the Catskill Mountain House in connection with the figure f of the rock below the house, the foliage g of trees, and road h below said house and rock. These figures illustrating the Catskill Mountain House, rock, foliage of trees, and road are grouped together in a panel at the 25 end portion a of the handle and bordered by scroll-work b, and preferably separated from the stem a' of the handle by the foliated scroll-work c, as shown in Fig. 1. On this stem portion a' of the handle is an oblong 30 panel for receiving letters or words, which panel is separated from the bowl A' by scroll-work i.

The leading features in the design for the reverse side of the handle are the figures k 35 of cats and panel D, neighboring said figures, for receiving letters or words, and figure n, illustrating a profile view of a mountain range. The figures of the cats and the panel

for receiving letters are on the outer end portion a of the handle and are preferably surrounded by scroll-work border d, while the profile view of the mountain range is on the stem portion a' and is shown to be separated from the bowl by the scroll-work m. These designs may be applied to the two opposite 45 (obverse and reverse) sides of handles of forks or analogous articles without involving invention by others.

What I claim is—

1. The design for the obverse side of the 50 handle herein described and shown, the same comprising the figure e of the Catskill Mountain House, figure f of the rock below said house, foliage g, and road h, as set forth.

2. The design for the reverse side of the 55 handle herein shown and described, the same comprising the figures k of the cats and a panel D for receiving letters, and the profile view or figure of a mountain range n, extended on the stem of the spoon, as set forth. 60

3. The design for the handle herein shown and described, the same consisting of the group of figures e of the Catskill Mountain House, f of the rock below said house, g of foliage, and h of a road, comprising the design for the obverse side, and the figure k of cats, panel D for receiving letters, and figure or view n of a mountain range, all together forming the reverse-side design, as set forth. 65

In testimony that I claim the invention 70 above set forth I affix my signature in presence of two witnesses.

JOHN T. HENDERSON.
